TEXTILE MACHINERY SPOOL AND CORE

Earl G. Crooks, Elmira, N. Y., assignor to Che-mung Engineering Corporation, Elmira, N. Y., a corporation of New York

Application October 24, 1931. Serial No. 570,830

12 Claims. (Cl. 242—118)

My invention relates to the spools employed in the textile industry and to the cores or spindles on which they are operatively supported.

Such spools are utilized, primarily, for holding thread which is wound thereon or unwound therefrom while the spool is supported on a suitable core or spindle, in turn generally supported in some form of textile machinery, but as the thread while on the spool is sometimes steamed or subjected to other operations in which the core is not required, it is desirable for this and other reasons that the spool be readily separable from the core.

My invention therefore contemplates the provision of a novel form of spool and a novel form of core adapted for assembly therewith to form an operative unit of such character that the spool will rotate with the core when the latter is driven and is also restrained from accidental or unintentional axial movement with respect thereto, so that the spool will remain firmly seated on the core through the various operations incident to its use in conjunction with the core although readily detachable therefrom when desired.

In consequence, through the medium of my invention, it is feasible to provide the various machines in a given establishment with the cores of my invention and to utilize throughout the plant but a single type of thread carrying spool adapted for assembly on any of the cores, thus eliminating the expense, confusion and annoyance incident to the present practice of using different types of spools and cores or other supporting means therefor for different operations and in connection with different machines.

A principal object of the invention, therefore, is the provision of an improved spool and core assembly so designed and constructed that when the parts are operatively associated the spool is firmly seated on the core, prevented from accidental or unintentional longitudinal separation therefrom or movement relative thereto and also constrained to rotate unitarily with the core although readily separable therefrom.

A further object of the invention is to provide a novel form of spool and also a novel form of core adapted for assembly therewith to form an operative unit, both capable of manufacture at a low cost, the spool being preferably made of a material which does not injuriously or otherwise affect the thread during the steaming or other operations to which it may be subjected either while disposed on or separated from the core.

A still further object of the invention is to provide a novel form of spool and core assembly of

such character that the core portion thereof may be more or less permanently arranged as an element of a textile or other machine adapted either to positively drive the core or to permit it to run freely so that the spools can be interchangeably seated on the cores when so arranged or detached therefrom when and as required, and the thread thus wound on the spool by rotating the core through the medium of the machine of which it forms a part or unwound therefrom as by allowing the core to run free and pulling off the thread, in accordance with the particular operation being performed, while by entirely removing the spool from the core the thread can be steamed or subjected to other treatment which might be injurious to the core although not inimical to the spool.

Additional objects, advantages and novel features of design, construction and arrangement comprehended by the invention are hereinafter more particularly pointed out or will be apparent to those skilled in the art from the following description of one embodiment thereof as illustrated in the accompanying drawing forming a part hereof and to which reference will now be made.

In the said drawing, Fig. 1 is a central longitudinal or axial section of the spool and core of my invention in operatively assembled relation, and Figs. 2 and 3 are respectively end elevations thereof. Fig. 4 is a transverse section through the spool shown in Fig. 1 removed from the core and substantially on the plane 4—4 looking in the direction of the arrows; Fig. 5 is a central longitudinal section of the spool on the plane 5—5 in Fig. 4, and Fig. 6 is a similar fragmentary section on the plane 6—6 thereof. Fig. 7 is a side elevation of the core apart from the spool; Fig. 8, an end elevation thereof looking toward the right, and Figs. 9 and 10, respectively perspective views of certain of the component parts of the core prior to assembly. Throughout the drawing, the same characters of reference are used to designate the same parts.

The spool S is desirably molded from heat resistant glass, such a spool forming the subject of a pending application for U. S. Letters Patent, Serial No. 531,442, filed April 31, 1931, by Earl G. Crooks and Charles H. Sayre, although other materials may be employed, if preferred, and is provided with an axial bore of relatively large diameter, preferably generally tapering from one end of the spool toward the other, this bore being formed during the molding operation by a plunger of corresponding external diameter through the

operation of which, in conjunction with the mold, a high degree of pressure is exerted on the plastic glass so as to cause the latter to properly conform to the mold cavity. The presence of this 5 relatively large axial bore thus serves, among other things, to structurally differentiate the spool from those commonly in use which comprise an axial bore of relatively small diameter, sometimes provided with a metal bushing or liner, through 10 which is inserted the spindle upon which the spool is supported when in use. Under practical conditions of manufacture, it has been found difficult to eliminate minor variations in diameter and taper in the bores of these molded glass 15 spools, and the core of the present invention is therefore designed, among other things, to suitably support and center the spools when assembled therewith irrespective of such variations and, in turn, to provide satisfactory means for receiving 20 the spindle or other part on which the core is ordinarily operatively mounted.

More particularly, the spool comprises, as usual, an exteriorly cylindrical body 1 through which extends the axial bore 2 to which reference has 25 just been made and adjacent the ends of which are flanges 3, 3' which assist in retaining the thread on the body, the former being disposed at what may, for convenience, be termed the base of the spool and the latter at its opposite or upper 30 end. The outer face of the flange 3 may be provided with an annular offset 4 surrounding the adjacent end of the bore 2 and chamfered at its junction therewith to provide an annular recess 5 for a purpose to be hereinafter described; 35 this recess is concentric with the axis of the spool and may be readily and accurately molded therein during its process of manufacture. Preferably, as stated, the bore 2 is inwardly tapered and thus slightly conical from the base of the spool toward 40 its upper end, and for a considerable distance beyond the base is of generally circular cross section. Toward its upper end, however, the bore is made of substantially polygonal cross section by providing it, as best shown in Fig. 4, with a plurality 45 of generally parallel lands 7 separated by grooves 8, the number of lands and grooves employed being a matter of choice, although six, as shown, will usually be preferred. These lands and grooves, the bottoms of the latter being in reality 50 merely extensions of the conical portion of the core, may be readily formed during the process of molding the spool by correspondingly shaping the end of the plunger which produces the bore.

Beyond the zone or area containing the lands 55 and grooves, the interior of the bore is preferably ground to produce an area or zone 9 of truly circular cross section and predetermined diameter and is outwardly beveled or flared as at 10 from the extremity of this zone to the end face 60 of the spool, this bevel being conveniently formed during the molding operation as it does not have to be absolutely accurate. For the reasons heretofore mentioned, some variation in diameter and taper will ordinarily occur in the bores of a 65 series of spools produced from the same mold, but of course the zone 9, which is ground after the molding operation is completed, can be made of constant diameter throughout the series and is preferably slightly tapered outwardly from its 70 point of minimum diameter at its junction with the major and unground portion of the bore.

Reference will now be made to the core C of my invention which is adapted for operative assembly with a spool of the character of that just 75 described and which, in the embodiment shown,

comprises a cylindrical body 15 of maple or other hard wood or, in fact, of any suitable material. This body is of suitable diameter to fit loosely in the bore of the spool and at its lower or right hand end, when viewed as in Figs. 1 and 7, is 80 provided with an integral flange 16 received in a metallic cup 17 having at its open end a peripheral flange 18 of suitable size and thickness to snugly seat in the annular recess 5 in the base of the spool when the core is assembled therein and thus center the core with respect to the adjacent end of the spool, the cup being desirably pressed or drawn from sheet metal and either frictionally retained on the flange or glued or otherwise secured in place thereon. Under certain conditions, the cup may be omitted and a peripheral flange corresponding to the flange 18 formed directly on the flange 16 for a like purpose, while the core will generally be provided with an axial hole 19 for the reception of a supporting spindle or the like. 95

Adjacent the opposite end of the core are disposed means adapted to prevent material rotation of the core when assembled within the spool and also to resist accidental or unintentional longitudinal separation of the parts, and while these means may be of any character suitable for the performance of their intended function, a preferred embodiment thereof comprises, as shown in the drawing, a plurality of symmetrically circumferentially spaced, generally longitudinally extending resilient elements 20 formed of spring steel or like suitable material and fixedly secured to the body 15 of the core. As best shown in Fig. 10, each of these elements may 100 comprise a central, generally flat and preferably slightly transversely curved body 21, a toe 22 and a heel 23. The toe is desirably bent slightly upwardly or outwardly from the body 21 and has its extremity still further outwardly bent to form 105 a detent 22' preferably disposed at an angle substantially conforming to the outward inclination of the beveled zone 10 adjacent the upper end of the spool, and may be oppositely inwardly tapered from its junction with the body 21 which 110 is a little wider than the toe so as to provide small shoulders 24 on each side of the latter. The heel portion 23 of the element extending from the opposite end of the body 21 is also preferably slightly narrower than the latter at its 115 junction therewith and is first bent upwardly or outwardly therefrom and then continued substantially parallel thereto so that when the element is assembled on the body of the core the heel, which is preferably transversely curved or 120 rounded and flared oppositely outwardly at its free end, will be spaced from said body for at least the major portion of its length. 125

Preferably, the number of elements provided is equal to one-half of the number of lands 7 in the 130 spool, although a greater or less number thereof with relation to the number of the lands may be utilized if desired; thus, when six lands are provided in the spool, three of the elements may desirably be utilized on the core and, as stated, symmetrically circumferentially spaced about and secured to the core body so as to extend parallel to its axis by any suitable means such, for example and as preferred, by a cylindrical ferrule 25, approximating in length the central portions 21 of the elements, which is seated over and constricted about the latter and the core body which is desirably reduced in diameter as at 26 to receive the ferrule and adjacent portions of the elements. Beyond the reduced area 26, the body of the core 135 140 145 150

is preferably still further reduced in diameter as at 27 so as to provide a shoulder 28 and the end of the ferrule turned in to form a flange 29 adapted to abut thereagainst, the flange being 5 suitably cut away as at 30 for the reception of the elements; thus, after the parts are placed in proper position and the body of the ferrule tightly constricted about the core body and the elements, the latter are held fixedly in position 10 with their toes 22 extending in radially spaced relation to the reduced extremity 27 of the core body and their heels 23 lying in similarly spaced and somewhat outwardly flaring relation to its main part behind the ferrule.

15 It will be understood, however, that while I prefer to secure the resilient elements to the core body in the manner to which reference has just been made since it affords a cheap, practical and efficient way of effecting the desired result, the 20 elements may be secured in place by any other suitable means if desired as long as the said means, whatever be the specific character thereof, are effective to secure the elements to the core in such way that their opposite ends are free to 25 yield slightly inwardly and then spring back to normal position when and as required.

It will now be apparent that a spool and core constructed substantially as described may be operatively assembled by pushing the core endwise into the bore of the spool or slipping the latter endwise over the core when the resilient elements are in substantial alignment with the grooves 8 between the lands 7 until the flange 13 is seated in the recess 5, the position of the resilient elements with respect to the body of the core and to the spool being so calculated that when the core is fully introduced, the detents 22' will extend slightly over the beveled zone 10 of the spool and thus yieldingly lock the core in the 40 spool against relative longitudinal movement in a direction opposite to that in which it was inserted, while the flange 13, of course, prevents its further longitudinal movement in the same direction. Additionally, the engagement of the toes of the resilient elements with the corner formed at the junction of the ground zone 9 and the beveled zone 10 of the spool serves to properly center the upper end of the latter on the core and thereafter maintain a substantially concentric 45 relation of the parts, while the transversely curved heels 23 of the resilient elements, by pressing into the grooves 8 between the lands 7, resist relative rotation of the core and spool sufficiently to insure unitary rotation thereof under any 50 operative conditions to which the assembly may be subjected. On the other hand, it will be equally apparent that the core and spool may be readily separated by pushing on the upper end of the core while holding the spool stationary, or by 55 holding the core stationary and pulling on the spool, with sufficient force to cause the detents 22' of the resilient elements to spring inwardly over the corner at the junction of the zones 9 and 10 and thence follow the wall of the spool bore as the 60 core is moved out of it. Moreover, as the rear ends of the lands 7 are preferably rounded as shown, the groove lying between each pair of lands is in effect provided with an inwardly tapering mouth which serves to guide the forward 65 ends of the elements 20 when the core is being inserted, thus substantially automatically bringing the elements to properly aligned position with respect to the grooves and facilitating assembly of the parts, the detents 22' of the elements 20 snapping into place over the corner of the junction of 70

the zones 9 and 10 just before the flange 13 is fully seated in the recess 5 and thus assisting to pull the latter longitudinally to its seat.

As will be readily understood by those skilled in the art, the cores of my invention may be mounted in any suitable way in connection with different machines adapted to positively drive the cores or to simply permit them to run idle so that when the spools are assembled thereon the threads may be either wound upon the spools or drawn off therefrom. In this respect and in many others as well, the core of the present invention is analogous to the cores disclosed and claimed in an application for U. S. Letters Patent filed by me October 2, 1931, under Serial No. 536,391, and, as more fully pointed out in that application, a desirable attribute of such cores resides in the fact that they may be mounted on spindles adapted to revolve in oil sealed bearings without interfering with the ability to assemble the spools on the cores or remove them therefrom, whereby the friction incident to the revolution of the spindles is minimized and the life of the parts correspondingly prolonged, the liability of thread breakage is reduced, possible contamination of the thread by the lubricant is avoided, and the spindles caused to run much more smoothly and to require less power to drive them than spindles mounted in plain unlubricated bearings in accordance with the customary practice.

While the cores of the present invention are particularly adapted for use in spools of the character of those forming the subject of my said application, Serial No. 531,442, which, in their preferred embodiment, are made, as hitherto stated, of heat resistant glass, they may be used with equal facility in connection with spools formed of other materials if desired, while as the spools and cores are interchangeable, standardization on a single type of spool and core in any given establishment is rendered possible, as any spool under such circumstances can be placed on any particular core and removed therefrom in a minimum of time.

While I have herein illustrated and described a preferred form of my invention in considerable detail, I do not thereby desire or intend to limit or confine myself to any specific embodiment of the principles thereof or to any precise details of design, construction or arrangement of the various parts so long as the same are within the spirit and scope of the invention as defined in the appended claims.

Having thus described my invention, I claim and desire to protect by Letters Patent of the 130 United States:

1. In combination, a spool having a bore embodying a region of non-circular cross section and a core removably seating in said bore and comprising a body of smaller diameter than the least diameter of the bore, means cooperative with said region to resist relative rotation between the spool and the core, means for centering one end of the core in the spool and means for centering the other end therein adapted to yieldingly resist relative axial movement between the spool and core comprising a plurality of resilient elements operative to engage the spool adjacent an end of the bore when the core is fully seated in the spool.

2. In combination, a spool having an axial bore 145 embodying a region of non-circular cross section and a recess adjacent one end of the bore, and a core having a body of smaller diameter than the least diameter of the bore removably seating therein and comprising at one end a flange co-

- operative with the wall of said recess to center the core with respect to the adjacent end of the spool, means cooperative with said region of non-circular cross section to resist relative rotation between the spool and the core, and resilient means at its other end adapted to yieldingly resist axial movement therebetween.
3. In combination, a spool having an axial bore embodying a region of non-circular cross section 10 and a recess adjacent one end of the bore, and a core having a body of less diameter than the least diameter of the bore removably seating therein and comprising means cooperative with said recess to center the core with respect to the adjacent end of the spool, means cooperative with said region of non-circular cross section to resist relative rotation between the spool and the core, and means adapted to yieldingly resist axial movement therebetween including a plurality of 20 resilient elements disposed in circumferentially spaced relation about the core and respectively provided with portions adapted to engage the spool adjacent that end thereof remote from said recess when the core is assembled in the spool.
25. 4. In combination, a spool comprising an axial bore having a region of polygonal cross section, a zone of circular cross section extending from said region toward one end of the spool, and a recess surrounding the end of the bore remote from said zone, and a core removably seating in the bore and comprising adjacent one end means cooperative with said recess to center the core in the spool and, adjacent its other end, a plurality of resilient elements respectively provided with portions adapted to engage said polygonal region to 30 resist relative rotation of the core and spool and other portions operative by yielding engagement with the spool adjacent said zone to yieldingly resist axial separation of the core and the spool.
40. 5. In combination, a spool comprising an axial bore having a region of polygonal cross section, a zone of circular cross section extending from said region toward one end of the spool, and a recess surrounding the end of the bore remote from said zone, and a core removably seating in the bore and comprising adjacent one end means cooperative with said recess to center the core in the spool and, adjacent its other end, a plurality of symmetrically circumferentially spaced 45 resilient elements extending parallel to the axis of the core and each comprising a toe portion adapted to engage the spool to yieldingly resist relative axial movement of the core and the spool, and a heel portion cooperative with said polygonal region to resist relative rotation therebetween.
55. 6. In combination, a spool having an axial bore extending therethrough, an outwardly beveled zone adjacent one end of the bore and a region within the bore of non-circular cross section, and a core removably seating in the bore and comprising a body, a plurality of resilient elements having their opposite extremities outwardly spaced from said body and respectively adapted to yieldingly engage said beveled zone to resist 60

axial separation of the core and the spool and to engage said non-circular region to resist relative rotation between the core and the spool.

7. In combination, a spool having an axial bore extending therethrough, an outwardly beveled zone adjacent one end of the bore, a region within the bore of non-circular cross section and a recess adjacent the other end of the bore, and a core removably seating in the bore and comprising a body, means cooperative with the recess to center the core in the spool, a plurality of resilient elements having their opposite extremities outwardly spaced from said body and respectively adapted to yieldingly engage said beveled zone to resist axial separation of the core and the spool and to engage said non-circular region to resist relative rotation between the core and the spool.

8. In combination, a spool having a bore embodying a region of polygonal cross section, an annular recess surrounding one end of the bore and an outwardly beveled zone of circular cross section adjacent its other end and coaxial with the spool, and a core removably seating in the bore and comprising means cooperative with the wall of said recess to center one of its ends in the spool, and resilient means cooperative with said outwardly beveled zone to center its other end therein.

9. A spool of the class described comprising an axial bore having a region bounded by alternating axially extending lands and grooves, a zone of circular cross section extending from said region to a point in proximity to one end of the spool and an outwardly beveled zone interposed between said circular zone and the adjacent end face of the spool.

10. A spool of the class described comprising an axial bore having an annular recess adjacent one end of the bore, a region within the bore bounded by longitudinally extending lands and grooves, a zone of circular cross section between said region and the opposite end of the bore, and an outwardly flaring zone extending from the end of the said zone of circular cross section.

11. A spool of the class described including a cylindrical body having a bore gradually inwardly tapering for the major portion of its length from a point adjacent one end of the spool to a point adjacent its other end, and then tapering outwardly toward said end, the walls of the respectively tapered portions of the bore forming opposite angles to the axis thereof.

12. A spool of the class described having an axial bore of least diameter at a point nearer one of its ends than the other, said bore comprising a portion gradually outwardly tapered with respect to its axis terminating in one end face of the spool, and another sharply outwardly tapering portion terminating in its other end face, the walls of said respectively tapered portions of the bore forming opposite but different acute angles with said axis.

EARL G. CROOKS.
